APPARATUS FOR FEEDING AND CLINCHING
CLINCH-ON NUTS AND THE LIKE

Frederick N. Ross, Grosse Pointe Park, Mich., assignor to Ash Products Corporation, Detroit, Mich., a corporation of Michigan

Application July 21, 1937, Serial No. 154,794

8 Claims. (Cl. 218—2)

My invention relates to apparatus for applying clinch-on nuts and the like to sheet material, usually steel sheets, and preferably including means for automatically feeding a succession of clinch-on nuts and the like to means for automatically clinching-on to sheet material the clinch-on nuts and the like.

Clinch-on nuts are applied to sheet material, usually steel sheets or formed steel sheet parts, for example in the manufacture of automobile bodies. Such manufacture is carried on by mass production methods, and a satisfactory machine for applying clinch-on nuts to steel sheet material in such manufacture must be capable of high speed and easy operation, and must also have a construction and arrangement of its parts, so as to minimize the possibility of jamming, and so as to enable breaking jams which may occur with no damage in most instances to the clinch-on nut applying machine.

Prior to the present improvements, clinch-on nut applying machines in use have not been entirely satisfactory, either in speed or ease of operation, or in performance with respect to jams.

The objects of the present improvements include the provision of improved apparatus adapted to be incorporated in a machine for applying clinch-on nuts and the like and including improved clinching means and improved means for feeding clinch-on nuts and the like to the clinching means, whereby the machine is capable of high speed and easy operation, with minimized jamming, and with relative ease in breaking jams.

Further objects of the improvements include the provision of improved general and detail arrangement of certain parts of the apparatus for attaining simplification, facilitating the manufacture, improving the operation, and facilitating the maintenance of the apparatus.

The foregoing and other objects are attained by the apparatus, parts, combinations, and sub-combinations, which comprise the present invention, and the nature of which is set forth in the following general statement, and preferred embodiments of which are particularly and distinctly pointed out and set forth in the appended claims forming part hereof.

The nature of the improved apparatus of the present invention may be stated in general terms as including improved reciprocating short-stroke anvil means and improved reciprocating peen plunger means, end faces of the anvil means and the peen plunger means being opposite each other for applying clinching pressure.

Improved reciprocating short-stroke tucker feed means are provided for feeding a succession of clinch-on nuts and the like onto the clinching face of the anvil means when the anvil means is displaced from its force applying position.

The peen plunger means is arranged to move towards the anvil means for applying clinching pressure when the anvil means is displaced towards the peen plunger means, preferably in a stationary position with back-up means opposing the clinching force and movement of the peen plunger means.

The peen plunger means is preferably provided with motor drive means.

The anvil means has preferably cam reciprocating and back-up means, and is preferably provided with independent preferably resiliently energized motor means for operating its reciprocating and back-up means.

The operation of the motor means for the anvil means is preferably controlled by the motor drive means for the peen plunger means, without any drive connection between the two motor means.

The anvil means and associated parts are furthermore arranged to facilitate the insertion and removal of a sheet into and out of position in the apparatus for having one or more clinch-on nuts applied thereto with a minimum of physical effort on the part of the operator.

The means and parts of the apparatus furthermore include improved details of construction and arrangement as are hereinafter set forth and claimed.

By way of example, embodiments of the improved apparatus hereof are included in a clinch-on nut applying machine illustrated in the accompanying drawings forming part hereof, in which

Figure 1 is a side elevation of the complete machine;

Fig. 2, an enlarged fragmentary view similar to Fig. 1 of the upper portions of the machine, with certain parts broken away or shown in section for the purpose of clearly illustrating the present improvements, the operating parts of the machine being shown in their relative positions, with the anvil of the present invention in the Up position with a clinch-on nut grasped by its jaws on its upper end ready for being applied to a sheet of steel or the like;

Fig. 3, a fragmentary front view thereof looking in the direction of the arrows 3—3, Fig. 2

with certain parts broken away or shown in section;

Fig. 4, a view similar to Fig. 2, but with the operating parts of the machine in their relative positions when the anvil is in its Down position, after the operation of applying by clinching-on, the nut shown on the upper end of the anvil in Fig. 2, to a sheet of steel, and with another nut fed into position on the upper end of the anvil by operation of the improved tucker nut feed means of the present invention;

Fig. 5, a fragmentary front view thereof similar to Fig. 3;

Fig. 6, a fragmentary sectional view thereof as on line 6—6, Fig. 4;

Fig. 7, a fragmentary plan view thereof as on line 7—7, Fig. 2 looking from above downwardly upon the improved tucker nut feed means and the improved anvil;

Fig. 8, an enlarged transverse sectional view thereof as on line 8—8, Fig. 7; and

Fig. 9, a view similar to Figs. 3 and 5, with the parts as shown in Fig. 5, in their relative positions after the anvil has returned to the Up position, elevating the sheet and applied nut of Fig. 5, upon the top of the nut grasped in the anvil, so as to permit easy and unrestricted removal of the sheet and applied nut.

Similar numerals refer to similar parts throughout the drawings.

The machine for applying clinch-on nuts, illustrated by way of example in the drawings, and including embodiments of the present improvements, is indicated generally by 10, and is particularly adapted for easy high speed operation, so that as many as 3,000 clinch-on nuts per hour may be applied or clinched-on to metal sheets and the like, usually steel sheets.

The clinch-on nut applying machine 10 as shown, includes a frame base 11, upon the top 11—1 of which is secured housing and mounting means indicated generally by 12, for the improved anvil means indicated generally by 13, the improved plunger means indicated generally by 14, and the improved operating and other associated parts therefor hereinafter described in detail.

The machine 10 furthermore includes a drive motor indicated generally by 15 which as shown is mounted in the base frame 11 below the top 11—1.

The housing and mounting means 12 operatively mounts the main drive shaft 16 as by bearings 17 and 18.

The main drive shaft 16 extends outwardly at the rear side 20 of the machine 10 beyond the housing and mounting means 12, and the rear end 21 of the shaft 16 beyond the housing and mounting means 12 has a driven pulley 22 secured thereon which is operatively associated through usual clutch means not shown and through usual belt means shown in part at 23 with the shaft 16 and with a drive pulley not shown on the shaft not shown of the motor 15.

The machine 10 is provided in a usual manner with actuating means, as shown a foot pedal 24, which is operatively associated in a usual manner with the clutch not shown, so that when the motor 15 is running, a downward pressure applied to the foot pedal 24 will cause one revolution of the main shaft 16.

The machine 10 is also provided with hopper means indicated generally by 25, which are operative in a usual manner to deliver a succession of clinch-on nuts N to the improved short-stroke

tucker feed means of the machine indicated generally by 26.

The housing and mounting means 12 is generally externally in the form of a U having a horizontal throat 27 opening towards the front or operating side 28 of the machine, the anvil means 13 being operatively mounted in the lower side portions indicated generally by 29 of the U housing and mounting means 12, and the plunger means 14 being operatively mounted in the upper side portions indicated generally by 30 of the U housing and mounting means 12.

The upper end face 31 of the anvil means is opposite the lower end faces 32 of the peen plunger means for applying clinching pressure therebetween.

The improved short-stroke tucker feed means 26 is provided for feeding a succession of clinch-on nuts N onto the upper clinching end face 31 of the anvil means 13 when the anvil means is displaced from its force applying position, preferably in its Down position as shown in Fig. 4.

The peen plunger means 14 is arranged to move toward the anvil means 13 for applying clinching pressure between the plunger face 32 and the anvil face 31 when the anvil means 13 is displaced towards the peen plunger means, preferably in a stationary "Up" position as shown in Fig. 2, in which the anvil means 13 is preferably provided with back-up means indicated generally by 33 opposing the clinching force or movement of the peen plunger means 14.

The peen plunger means 14 reciprocates preferably vertically within and between the inner faces of guide tube portions 34 of the upper side portions 30 of the U housing and mounting means 12.

The preferred short-stroke reciprocation of the peen plunger means 14 is preferably effected from the electric motor driven shaft 16, the forward end 35 of the shaft 16 being provided with a short-stroke operative connection indicated generally by 36 with the upper end 37 of the peen plunger means 14 for effecting short-stroke reciprocation of the peen plunger means 14 by rotation of the shaft 16.

As shown, the operative connection 36 between the shaft 16 and the peen plunger means 14 includes a forwardly extending crank pin 38 provided on the forward extremity of the forward end 35 of the shaft 16, and a slide block 39 is arranged for transverse sliding in a transverse guide groove 40 formed in the upper end 37 of the peen plunger means 14, the crank pin 38 extending into a suitable bore provided in the slide block 39, whereby short-stroke reciprocation of the peen plunger means is effected when the shaft 16 rotates.

The anvil means 13 reciprocates preferably vertically within and between the inner faces of guide portions 41 of the lower side portions 29 of the U housing and mounting means 12.

The preferred short-stroke reciprocation of the anvil means 13 is preferably effected by reciprocating cam means indicated generally by 42 which also preferably include the back-up means 33.

Independent preferably resiliently energized motor means 43 is provided for actuating the reciprocating cam and back-up means 42 and also preferably for actuating the tucker feed means 26.

The operation of the motor means 43 for the cam and back-up means 42 and the tucker means 26 is preferably controlled by the motor drive

means for the peen plunger means 14, preferably as shown by cam and follower means indicated generally by 44 interposed between the peen plunger drive shaft 16 and the motor means 43 as hereinafter set forth in detail, the cam and follower means 44 being arranged so that there is no drive connection between the shaft 16 and the motor means 43, the function of the cam and follower means 44 being only to permit movement of the motor means 43.

The preferred resiliently energized motor means 43 is located within the housing and mounting means 12, and as shown includes a T crank indicated generally by 45 which is pivotally mounted intermediate the shaft 16 within the interior compartment 46 of the housing and mounting means 12, as by a pivot screw 47 which as shown extends through a pivot bore 48 of the T crank 45 located at the junction of the depending stem arm 49 of the T crank 45 with the oppositely extending head arms 50 and 51 thereof, the pivot screw 47 being screwed into one of the side walls 52 of the housing and mounting means 12.

The head arm 50 of the T crank 45 extends rearwardly from the pivot screw 47 and a resilient spring 53 has its upper preferably hook end 54 engaged with one of a plurality of apertures 55 provided adjacent the extremity of the head arm 50, and the lower preferably hook end 54' of the spring 53 is engaged with an anchor pin 56 secured in one or more of the walls of the housing and mounting means 12.

The resilient spring means 53 as shown is a helical tension spring, and tends to urge the T crank 45 in the direction of the arrow 57.

The cam and follower means 44 is interposed between the shaft 16 and the other head arm 51 of the T crank 45 of the resilient motor means 43, and the cam and follower means 44 includes a rotary disk cam 58 secured upon the shaft 16 and preferably having a cam profile 59 as shown in Fig. 6, and against which rolls the outer periphery 60 of a roller cam follower 61 journaled on the outer end of the head arm 51 of the T crank 45.

The motor means 43 furthermore includes, within the compartment 46 of the housing and mounting means 12, a carriage block 62 which is arranged for forward and rearward reciprocation, as by a plurality of roller and slot means 63 each of which as shown includes a forward and rearwardly directed slot 64 formed in the carriage block 62, the side faces of each slot being adapted for rolling on the periphery of a roller 65 which it rotatably mounted on one of the walls 52 of the housing and mounting means 12.

There is provided between the carriage block 62 and preferably the lower end of the stem arm 49 of the T crank 45, pin and slot connecting means 49-1.

The reciprocating cam and back-up means 42 includes a forwardly and rearwardly extending cam and back-up bar 66 located within the interior compartment 46 of the housing and mounting means 12, and the rear end of the bar 66 is secured as by screws 67 upon the lower side 68 of the carriage block 62 of the motor means 43.

The tucker feed means 26 includes a tucker bar 69 located within the interior compartment 46 of the housing and mounting means 12, and the rear end of the tucker bar 69 is secured as by screws 70 upon the upper side 71 of the carriage block 62.

The forward wall 72 of the lower side portions 29 of the U housing and mounting means 12 has formed therein a forwardly and rearwardly directed opening 73 into which extends the forward end 74 of the bar 66 of the cam and back-up means 42, and one side face 75 of the forward end 74 of the bar 66 has formed therein a side-wardly opening cam slot 76.

The lower end of the anvil means 13 is provided with a downwardly extending tongue 77 extending opposite the side face 75 of the bar 66 in which the cam slot 76 is formed and a cam follower pin 78 is secured in and extends from the tongue 77 of the anvil means 13 into the slot 76 of the cam and back-up bar 66.

The forward end 74 of the cam and back-up bar 66 is enlarged as best shown in Figs. 2, 3, and 4, forming the back-up means or head 33 so that its upper face 79 is arranged for reciprocation into and out of abutment with the lower face 80 of the anvil means 13.

The anvil means 13 includes preferably as shown an elongated anvil bar 81 upon which is formed the upper clinching anvil face 31 and the lower abutment face 80, and from which as shown integrally extends the tongue 77.

The upper end of the anvil bar also preferably includes as shown a forward nut stop 82 extending above the clinching face 31.

At one side of the anvil bar 81, a preferably stationary nut side clamp jaw 83 is provided, and at the other side of the anvil bar 81, a yieldable nut side clamp jaw 84 is operatively mounted as by pin and aperture means 85 and tension spring means 86.

As shown, the peen plunger means 14 includes a vertically elongated plunger cylinder 87 having a downwardly opening bore 88 formed therein, the cylinder 87 reciprocating within and between the inner faces of the guide tube portions 34 of the upper side portions 30 of the U housing and mounting means 12 and including the upper end 37 which is provided with the operative connection 36 with the shaft 16, as aforesaid.

Within the lower end of the downwardly opening bore 88 of the plunger cylinder 87, a plunger head 89 is mounted for limited slidable movement therein, as by oppositely arranged pin and slot means 90 interposed between side wall portions 50 of the plunger cylinder 87 and the plunger head 89, as best shown in Figs. 3 and 4.

A compression spring 91 is located within the bore of the cylinder 87 and reacts against the upper end face 92 of the plunger head 89 and the opposite end face 93 of the cylinder bore 82, whereby limited yielding movement of the plunger head 89 with respect to the plunger cylinder 87 is permitted.

The plunger head 89 preferably has removably mounted therein a plunger clinching die 94 having the clinching faces 32 formed thereon; and the spring pressed yieldable mounting of the plunger head 89 in the plunger cylinder 87 permits the plunger means 14 to accommodate itself to slight variations in the vertical heights of the nuts N applied by the improved machine 10 as set forth hereinafter.

The tucker feed means 26 includes in addition to the tucker bar 69, forwardly and rearwardly extending nut guide means indicated generally by 95 which as shown comprises the lower side of the horizontal U throat 27 and include a bottom elongated nut slide plate 96 and oppositely spaced nut side guide bar means 97 and 98.

The nut guide means 95 is arranged to receive at one side, nuts from the delivery trough 99 of the hopper means 25, as shown, at the rear of the nut side guide bar means 98 adjacent the rear wall 100 of the U throat 21 of the housing and mounting means 12, and the U throat rear wall 100 has formed therein a forwardly and rearwardly extending opening 101 into which extends and reciprocates the forward end of the tucker bar 69.

The forward end of the nut guide means 95 communicates with the upper end of the guide portions 41 for the anvil means 13.

As best shown in Fig. 8, the bottom plate 96 of the nut guide means 95 is preferably removably secured upon the lower side portions 29 of the U housing and mounting means 12, as by being formed with a U cross section having outer depending legs 102 and 103 which fit about a tongue 104 of the lower side portions 29 of the U housing and mounting means 12, and which are secured thereto as by transversely extending screw means 105.

The nut side guide bar means 98 is preferably as shown removably secured upon the upper face of the slide plate 96 as by screw means 106 for permitting removal of the guide bar means 98 in case of jamming of the machine 10.

The nut side guide bar means 98 is preferably as shown, provided with front and rear spring pressed nut-clamping plunger means 107 and 108.

The guide portions 41 for the anvil means 13 preferably as shown, include oppositely spaced side members 109 and 110, the upper ends of which are arranged to support a sheet of material S thereon when the anvil means 13 is in retarded or Down position, as shown in Figs. 4 and 5.

The cam slot 76 of the bar 66 includes a forward portion 76-1 at an angle, preferably at a right angle with the direction of movement of the anvil means 13, an intermediate portion 76-2 sloping with respect to the forward portion 76-1, and a rear portion 76-3 parallel with the forward portion 76-1, the cam slot portions 76-1, 76-2 and 76-3 having adjacent ends communicating with each other.

The machine 10 is shown as applying the clinch-on nuts N which include the improvements of my application for U. S. Letters Patent for Clinch-on nuts and method of forming the same, Serial No. 140,217, each nut N including an enlarged head or seat portion N-1 from which extends a reduced clinch-on wall or shank portion N-2, each nut N having a threaded bore N-3 which terminates at the clinch-on end in a tapered portion N-4.

The machine 10 is however adapted for applying other forms of clinch-on nuts or similar articles to sheet metal S and the like.

In the operation of the machine 10, the hopper means 25 delivers a succession of nuts N and the like into the rear end of the guide means 95 from where the nuts N are successively pushed forward by successive reciprocations of the tucker bar 69 so as to fill the guide means 95, as best shown in Figs. 2, 3, and 7.

The front and rear spring pressed clamping plunger means 107 and 108 serve to yieldingly maintain the nuts N in the guide means 95 in front and rear abutment with each other so that the forward nuts N in the guide means 95 are successively fed upon the clinching face 31 of the anvil means 13.

The parts of the machine 10 are shown in Figs. 75

2 and 3 in their relative positions with the anvil means 13 in its extreme Up position of displacement, and backed-up by the back-up portion 33 of the cam and back-up bar 66, ready for a sheet of material having a suitable aperture formed therein to be placed on the shank N-2 of the nut N located upon the clinching end face 31 of the anvil means 13 with its forward end face in abutment with the stop 32 and with its side faces releasably clamped by the clamp jaws 83 and 84. In this position, the low portion of the cam 58 is toward the observer in Fig. 2.

When a sheet of material S having a suitable aperture formed therein is applied to the nut N located on the clinching face 31 of the anvil means 13, and the parts of the machine 10 are in the relative position shown in Figs. 2 and 3, and the foot pedal 24 is depressed, the shaft 16 makes one revolution counterclockwise as seen in Fig. 3, first causing descent of the peen plunger means 14 so as to clinch the nut N on the opposite clinching face of the anvil means 13 onto the sheet S, and at the same time causing rotation of the disk cam 58, the high portion of which during the descent of the plunger means 14 maintains the T crank 45 in its position with its stem arm 49 to the rear as shown in Fig. 2, and bringing during the ascent of the plunger means 14 the low portion of the cam 58 in opposition to the roller cam follower 61 on the T crank 45 of the resilient motor 43, permitting the spring 53 thereof to swing the T crank 45 so that the stem arm 49 moves forwardly advancing the motor carriage block 62 and the cam bar 66 and tucker bar 69 secured thereto, so as to simultaneously retract the anvil means 13 away from the plunger means 14 by the action of the cam slot 76 on the cam follower pin 78 as the cam bar 66 advances, and feed another nut N upon the retracted upper clinching surface 31 of the anvil means 13 beneath the nut N which has just been clinched onto the sheet S, the sheet S being supported on the upper ends of the anvil means side guides 109 and 110 as shown in Figs. 4 and 5.

Three-quarters rotation of the shaft 16 serves to change the relative positions of the parts of the machine 10 from those shown in Figs. 2 and 3 to those shown in Fig. 4, and a further one-quarter rotation of the shaft 16 serves to return the parts of the machine to the relative positions shown in Figs. 2 and 3; under which conditions the nut N applied to the sheet S is supported on the upper end of the following nut N fed onto the clinching face 31 of the anvil means 13 by operation of the tucker means 26, as shown in Fig. 9.

The final position of the sheet S with the clinch-on nut N applied thereto supported on the lower nut N as shown in Fig. 9, permits free removal of the sheet S and applied nut N from the machine 10, without requiring the operator to fight the machine in order to remove the sheet S with the applied nut N thereon, as is the case in certain other forms of machines for applying clinch-on nuts.

All the reciprocating parts of the machine 10 including the present improvements as above described, have short-stroke reciprocations, thus permitting high speed operation of the machine; and the association of the plunger reciprocating means with its separate motor drive, and the anvil and tucker feed actuating means with their independent motor drive is such as to minimize both frequency and severity of jamming, a result

also attained by the details of construction and arrangement of the parts of the machine.

The embodiments of the improved apparatus for feeding and clinching clinch-on nuts and the like illustrated and described herein attain the above stated objects of the invention, but are by way of example, and the scope of the present invention is not limited to the same or to the particular details thereof, but is commensurate with any and all novel subject matter contained herein, and which may at any time properly under the patent laws be set forth in claims hereof or which may originate herein, the elements of any of the claims being intended to include their reasonable equivalents.

I claim:

1. In a machine of the character described, an anvil, a plunger, said anvil and said plunger being reciprocable toward and away from each other and having opposed work engaging surfaces, a rotatable shaft, crank means on said shaft and operable to actuate said plunger, a reciprocable member, means carried by said reciprocable member to actuate said anvil, means carried by said reciprocable member to feed clinch-on nuts or the like onto said anvil, cam means on said shaft and operable to reciprocate said member, and means operatively connecting said cam means and said reciprocable member.

2. In a machine of the character described, an anvil for supporting clinch-on nuts or the like, a plunger, said anvil and said plunger being reciprocable toward and away from each other and having opposed surfaces, means providing a supporting surface for clinch-on nuts or the like, said anvil being movable to one position wherein its said surface is substantially in the same plane with said supporting surface, a reciprocable carrier member, a rod member carried by said carrier member below said nut supporting surface and having a cam surface operable to move said anvil from said one position toward said plunger, a push rod carried by said reciprocable member above said nut supporting surface and operable to successively position the nuts on said anvil surface, means to reciprocate said plunger, and means operatively connecting said last-named means and said reciprocable member.

3. In a machine of the character described, an anvil, a plunger, said anvil and said plunger having opposed surfaces and movable toward and away from each other, a shaft, crank means on said shaft operable to reciprocate said plunger, cam means on said shaft, a lever arranged to pivot in one direction by said cam means, a reciprocable member connected to and movable in one direction by said lever upon pivoting of said lever by said cam means, cam means carried by said reciprocable member and operable to move said anvil toward said plunger, and spring means operable on said lever to pivot said lever in the opposite direction.

4. A machine of the character described, comprising a set, means to operate said set, an anvil movable into and out of operative relation with said set, a channel for feeding upsettable members onto said anvil, means to reciprocate said anvil into and out of operative relation with said set, said anvil in its retracted position being substantially in alignment with the bottom of said channel, a source of upsettable members communicating with said channel, means to feed a single upsettable member from said source into said channel and at the same time another up-

settable member from said channel onto said anvil, and a connection between said anvil moving means and said feeding means to actuate said feeding means to feed, when said anvil reaches its retracted position, an upsettable member into said channel from said source and another upsettable member from said channel onto said anvil.

5. In a machine of the character described, 10 an anvil for supporting clinch-on nuts or the like, a ram, said anvil and ram being reciprocable toward and away from each other and having opposed surfaces, means providing a supporting surface for clinch-on nuts or the like, said anvil being movable to one position wherein the said surface is substantially in the same plane with said supporting surface, means below said nut supporting surface and having a cam surface operable to move said anvil from said one position toward said ram, a feeding means adjacent said nut supporting surface and operable to successively position the nuts or the like onto said anvil surface, and a connection between said anvil moving means and said feeding means to actuate said feeding means to position, when said anvil reaches said one position, a clinch-on nut or the like on said anvil.

6. A machine of the character described, comprising a set, means to operate said set, an anvil movable into and out of operative relation with said set, an anvil guiding slideway along which said anvil moves, a channel for feeding upsettable members, communicating with said slideway, means to reciprocate said anvil in said slideway into and out of operative relation with said set, said anvil in its retracted position being substantially in alignment with the bottom of said channel, a source of upsettable members communicating with said channel, means to feed a single upsettable member from said channel onto said anvil, and at the same time to feed another upsettable member from said source into said channel, and a connection between said anvil moving means and said feeding means to actuate said feeding means to feed, when said anvil reaches its retracted position, an upsettable member into said channel from said source and another upsettable member from said channel onto said anvil.

7. A machine of the character described, comprising a set, means to operate said set, an anvil movable into and out of operative relation with said set, an anvil guiding slideway in which said anvil moves, upsettable member conducting means for presenting upsettable members adjacent the said slideway, said anvil in retracted position being at least in clearing relation to the plane of said conducting means, means to move said anvil into and out of operative relation with said set, means to feed a single upsettable member from said conducting means into said slideway for disposition on said anvil, and an operative, coordinating connection between said anvil moving means and said feeding means to actuate said feeding means to feed, when said anvil has cleared the plane of said conductor in its retracting movement, an upsettable member into said slideway for disposition on said anvil.

8. A machine of the character described comprising a set, means to operate said set, an anvil movable into and out of operative relation with said set, means providing a conductor for upsettable members for positioning them adjacent the path of said anvil, means to reciprocate said anvil into and out of operative relation with

said set, said anvil in its retracted position being clear of the plane of said conducting means, means to feed an upsettable member from said conducting means onto said anvil, a connection between said anvil moving means and feeding means to actuate said feeding means to feed, when said anvil reaches its retracted position,

5 an upsettable member onto said anvil, and spring means operatively associated with said anvil moving means and feeding means for controlling the respective movements of said means in one direction.

FREDERICK N. ROSS.
